UNITED STATES PATENT OFFICE.

ELLIS EDWARD ADAMS AND EDWARD CLAUDIUS BENNETT, OF ROANOKE, VIRGINIA.

AUTOMATIC TRAIN-STOP.

1,377,955.

Specification of Letters Patent. Patented May 10, 1921.

Application filed July 21, 1919. Serial No. 312,179.

To all whom it may concern:

Be it known that we, ELLIS E. ADAMS and EDWARD C. BENNETT, citizens of the United States, residing at Roanoke, in the county of 5 Roanoke and State of Virginia, respectively, have invented new and useful Improvements in Automatic Train-Stops, of which the following is a specification.

This invention relates to an automatic 10 train stop and has for its primary object the provision of an electrically operated means for closing a throttle valve and applying the air brakes in conjunction with other means coöperating with the first means for giving 15 visual indications in the cab of the locomotive of the condition of the advance block.

Another object of the invention is to provide simple mechanism for closing a throttle lever and upon the throttle lever reaching 20 said closed position, to open the train line into communication with the atmosphere so as to apply the air brakes of the train.

A further object of the invention is to so construct and arrange the parts that the 25 number of parts necessary in an apparatus of this character is materially decreased without sacrificing the efficiency thereof.

With these and other objects in view the invention will be better understood from 30 the following detailed description taken in connection with the accompanying drawings, wherein:

Figure 1 is a diagrammatic view of the system.

Fig. 2 is a diagrammatic view partly in 35 section of the mechanism for closing the throttle lever and bleeding the train line.

Fig. 3 is an enlarged sectional view through the air motor showing the piston in 40 position to establish communication between the train line and the atmosphere.

Figs. 4 and 5 are views of the track obstacles.

Fig. 6 is a sectional view through the 45 electric catch.

Fig. 7 is a diagrammatic view illustrating how the switch coöperates with the recorder.

Fig. 8 is a diagrammatic view of a second 50 form of mechanism coöperating with the throttle lever and setting the air brakes.

Again referring to the drawings illustrating one of the many forms in which the invention may be constructed, the letter B designates the railroad block while the letter 55 C designates the semaphore arranged at the

junction of two blocks. A short distance from each semaphore we have arranged a pair of track obstacles 1 and 2 the former to be known as the "caution obstacle" and the latter as the "danger" obstacle. Each 60 obstacle consists of a shaft 3 mounted for rotation in bearing 4, Figs. 4 and 5, and having a crank portion 5 connected to a plunger 6. This plunger 6 is actuated by a solenoid 7 arranged in a circuit 8 including 65 a source of current 9 and opened and closed by the movement of the semaphore, that is to say when the semaphore moves to caution position it will close the circuit of the obstacle 1 whereas when the semaphore moves 70 to danger position it will close the circuit of obstacle 2. One end of each shaft 3 has connected thereto a weight 10 for normally holding the shaft in a predetermined position while the other end of the shaft is 75 formed into a plate 11 adapted when in active position to be arranged in the path of movement of certain elements on the train. In the use of my invention it is not necessary to change the throttle lever 12 with the 80 exception of providing a pin 13 on a dog or latch 14 against which acts the cam surface 15 of a slide 16. This slide 16 is connected to the stem 17 of a piston 18 slidably mounted in a cylinder 19. Communicating with 85 the cylinder 19 at one side of the piston 18 is a pipe 20 passing to the main air reservoir of the air brake system. This pipe 20 has arranged therein a valve 21 of any well known construction having a connection 22 90 with the plunger 23 of a solenoid 24. The cylinder is provided with a bleed port 25 of a very small diameter when compared with the diameter of the pipe 20 so that when the valve 21 is opened air will enter the cylinder 95 and move the piston to its limit of travel. As soon as the valve 21 is closed air will bleed through the port 25 and allow the piston 18 to be returned with the return of the throttle lever to open position. The advantage of this construction is that the throttle lever may be moved any required distance and the piston 18 will be in the proper position to be acted upon by the air for closing the throttle lever.

Also formed in the cylinder is a pair of ports 26 and 27 the latter communicating with the atmosphere while the former communicates with a branch pipe 28 in communication with the main train line 29 of 110

the usual air brake system. The piston is formed with an extension 30 acting as a slide valve so that when the bypass 31 in the piston does not establish communication 5 between the ports 26 and 27 these ports will be closed thereby preventing escape of air from the train line when the said bypass of the piston is not positioned over the ports. Attention is called to the fact that 10 under normal conditions the piston 18 is at its limit of travel in the left hand direction as indicated in Fig. 2, and therefore the throttle lever is free to move back and forth without actuating the slide 16 but 15 should the throttle lever be completely opened or partly opened the lever will be thrown to closed position upon air entering the cylinder owing to the fact that the piston 18 will travel the required distance. 20 At this point it is to be understood that the lever 12 is first unlocked and thereafter the throttle is closed by the movement of the rod 16.

It will be understood in this connection 25 that the widened extension of the rod 16 co-acts with the slotted bracket carried by the throttle lever to close the throttle.

Another form of mechanism for closing the throttle lever 12 is shown in Fig. 8 consisting of an air motor 60 having a connection 61 with the throttle lever. Air under pressure is allowed to pass to the motor by the electrically controlled valve 62. When the piston 63 of the air motor has traveled 30 a predetermined distance a pipe 64 is thrown into communication with the pipe 65 in which the valve 62 is arranged for allowing the air pressure to operate a second motor 66. This motor 66 operates the bleed valve 40 67 arranged to coöperate with an L-shaped link 68. The bleed valve 67 is arranged in connection with the train line 69 so as to bleed air to the atmosphere and thereby reduce the train line pressure for setting the 45 air brakes under pressure conditions.

Having described the mechanical elements coöperating with the throttle lever and putting into motion the air brake apparatus of the train we will now describe the circuits 50 whereby signals will be given the engineer and upon a certain signal being displayed the throttle lever will be thrown to closed position and the train line bled so as to apply the air brake system. Arranged in the 55 cab of the locomotive are a yellow electric bulb 32, green bulb 33 and red bulb 34, designating respectively "clear," "caution," and "danger." The bulb 33 is arranged in an open circuit including a conductor 35 that receives current from a generator 36. Arranged in said open circuit is a manually 60 operated double pole knife switch 37. A branch circuit including conductors 38 also feeds current from the generator to the said 65 open circuit and has arranged therein a

double pole knife switch 39 and thus it will be seen that it will be necessary to open both switches 37 and 39 to prevent current from passing from the generator to the open circuit including conductors 35. The object of this arrangement is that the engineer as well as the fireman must open a switch before the supply of current to the circuit is cut off. The open circuit including the conductors 35 is interrupted at the point 70 36^x and arranged at this point is a pair of spaced contacts 40, arranged to be bridged by a blade or arm 41 when the same is struck by a track obstacle. In order to hold the arm 41 in a position to bridge the contacts 40 when the arm has been struck by an obstacle, we have provided an electric latch in the form of a solenoid 41^b in which is mounted a spring pressed plunger 42, Fig. 6, arranged to extend under the arm 41 when 75 the solenoid 41^b is energized. This solenoid 41^b is arranged in a circuit including a conductor 43 that has one terminal connected to the contact 44 arranged contiguous to the contacts 40 so as to be engaged when the arm 41 is thrown about its pivot 45. Comprised in this conductor 43 is a thermostatic 80 type of switch 46 which in one of the forms may be constructed of two strips of dissimilar material having different degrees of expansion so as to move out of engagement with the contact 47 when the strips are heated due to the passage of current to the solenoid 41^b. As far as we have proceeded 85 it will be seen that when one of the track obstacles have been thrown to active position due to the movement of the semaphore blade C the arm 41 will engage the obstacle in the passage of the train and thereby be thrown about its pivot and electrically connecting the contacts 40 and contact 44 thereby closing the circuit including the conductors 35, sounding an audible signal 35^x and illuminating the green lamp 33 and allowing current to pass through the solenoid 41^b for forcing the plunger 42 in position 90 to prevent return movement of the arm 41. When the arm 41 is raised by the obstacle 11, the plunger 42 assumes a position 95 under the arm 41 as shown in Fig. 6. The arm 41 will be retained in this position a predetermined degree of time until the thermostatic blade 46 moves to a position to open the conductor 43 whereupon the solenoid 41 will be deenergized and the spring 100 pressed plunger 42 allowed to return to normal position, releasing the arm 41 and permitting the same to gravitate to normal position. At this point it will be understood that after the lapse of a short period 105 of time the thermostatic blade 46 will operate automatically to close the gap in the conductor 43, and thereby reset the apparatus. The bulb 32 is arranged in a circuit 110 including a conductor 48 one terminal of 115

which is connected to one conductor 35 of the circuit before described while the other terminal is connected to the other conductor of the said circuit and thus the bulb 32 is continuously illuminated unless interrupted in a manner now to be described. Arranged in the circuit including the conductor 48 is a switch 49 normally held in closed position by a spring 50. This switch is arranged to be opened by a magnet 51 arranged in the circuit including a conductor 52 that has one terminal connected to one of the conductors 35 of the before mentioned open circuit while its other terminal is connected to one of the contacts 54^x. Arranged in a circuit including a conductor 52^x is a red bulb 34 known as "danger." This conductor 52^x is interrupted at the point 53 similarly to the circuit 35 and arranged at this point are three contacts 54^x adapted to be electrically connected by another arm 55 when it strikes its associated track obstacle. An electric latch 56 similar to the one just described is arranged to retain the arm 55 in circuit closing position and is arranged to operate upon the switch blade being thrown to a position to close the circuit including the conductors 52 and 52^x. Tapped onto the conductor 52^x is a conductor 57 connected to the solenoid 24. To complete our invention, we place adjacent to each switch 37 and 39 a recorder 58 the operating arm 59 of which extends over the switch so as to be operated in the movement of the switch.

The operation of the system is as follows:—Upon the semaphore blade C moving to caution position it will close circuit 8 and thereby energize the solenoid of track obstacle 1 which throws the same to active position so that upon a train approaching the semaphore C the switch arm 41 will strike the obstacle and be thrown about its pivot so as to electrically connect the contacts 40 and 44. When this takes place the caution signal 33 will be energized and current will be free to pass through the electric catch 41^b for preventing return movement of the switch arm 41. Thus the engineer 50 is given an audible signal and a visible signal as to the condition of the semaphore blade and the block that it protects and after these signals 33 and 35^x have been actuated for a predetermined interval of time 55 the thermostatic switch 46 will be properly heated and owing to its construction will bow or bend in a direction to break the circuit to the catch 41^b thereby allowing the switch arm 41 to gravitate to normal position. Should the semaphore blade C move to danger position instead of caution the circuit 8^x will be closed thereby setting into action the track obstacle 2. The train in passing the track obstacle 2 which is now 60 in active position will bring the arm 55 into

engagement with the blade 11 thereby throwing the switch arm 55 about its pivot and bridging the contacts in the same manner as described with relation to the contacts of the caution circuit. As soon as the 70 circuit including the conductor 52 is closed a solenoid 51 arranged in said circuit operates a switch to break the continuity of the circuit in which the normally energized clear signal 32 is arranged. When the danger circuit is closed the solenoid 24 is energized which retracts its core 23 and thereby 75 opens the valve 21. When the valve 21 is opened air passes from a main reservoir to the cylinder 19 where it will act upon the piston 18 and close the throttle valve. Upon travel of the piston 18 a predetermined distance the ports 26 and 27 will be thrown into communication with each other for bleeding a certain amount of air from the 80 train line which immediately sets the air brake into operation.

It will be apparent from the foregoing that when either the switch 37 or the switch 39 is closed the branch circuit including the 90 conductors 38 will be connected with the open circuit including the conductors 35. Therefore when the arm 41 electrically connects the contacts 40 and 44 the course of the current will be from one pole of the 95 generator 36 through the lower conductor 38 through the lower or feed conductor 35, and then by way of the inner contact 40 to the arm 41, and then by way of the outer contact 40 and the outer or upper conductor 100 35 to the upper or outer conductor 38 and back to the other pole of the generator. At the same time current will pass from the lower or feed conductor 35 through the inner contact 40 and the arm 41 to the contact 105 44 and from thence to solenoid 41^b and then through the conductor 43, the thermostatic switch 46 and the upper or return contact 35 to the last mentioned pole of the generator 36. Thus so long as the contacts 40 110 are electrically connected the filament of the lamp 33 will be caused to glow, and the bell 35^x will be sounded. It will be remembered here that the arm 41 is permitted after the lapse of a short period of time to 115 gravitate away from and thereby interrupt the connection between the contacts 40. When the arm 55 is moved to electrically connect the contacts 54^x, the course of the current from one pole of the generator 36 120 will be through the lower or feed conductor 35, then by conductor 80 to the electromagnet 51, then by conductor 52 to the outer contact 54^x then by the arm 55 to the intermediate contact 54^x then by wire 125 52^x to the filament of the lamp 34, and then by conductor 81 to the upper or return conductor 35. At the same time current will pass from the conductor 52^x through the conductor 57 to the solenoid 24 and then 130

by conductor 57* to the upper or return conductor 35 and thence to the opposite pole of the generator 36. Also at the same time current will pass from the lower or feed conductor 35 through conductor 82 to solenoid 56, and from said solenoid through the inner contact 54* and the arm 55 and then by way of the conductor 52*, lamp 34 and conductor 81 to the return conductor 35 and back to the other pole of the generator 36. It will also be apparent that when either of the switches 37 or 39 is closed, and the arms 41 and 55 are positioned as shown in Fig. 1, the course of the current from one pole of the generator 36 will be through the lower or feed conductor 35 through a conductor 85 to the filament of the lamp 32, and from the said filament of the lamp 32 the current will pass through a conductor 86, the switch 49 and a conductor 48 to the upper or return conductor 35 through the latter to the opposite pole on the generator 36. During this passage of the current the lamp 32 will be caused to glow and the persons in authority will be apprised of the fact that the system is in good working order. It will be noticed, however, that when the arm 55 electrically connects the contacts 54* the magnet 51 will be energized and by attracting the switch 49 will interrupt the connection between the conductors 86 and 48, so that the lamp 32 will be extinguished.

From the foregoing description taken in connection with the accompanying drawing it will be seen that we have provided a simple inexpensive apparatus for applying the air brakes of a train and closing the throttle valve upon the train entering a danger block and besides give visible signals in the cab of the locomotive as to the position of the semaphore blade of the block that the train is approaching. It is of course to be understood that this invention may be constructed in various manners and parts associated in other relations and therefore we do not desire to be limited in any manner except as set forth in the claims hereunto appended.

50 What we claim is:—

1. An automatic train stop system comprising semaphore controlled track, obstacles, train carried signal circuits to be closed by said obstacles another signal circuit controlled by one of the first mentioned circuits, and manually operated switches for opening all of said first mentioned circuits,

and a recorder operated in opening each of said switches.

2. An automatic train stop system comprising a semaphore controlled track obstacle, a train carried signal circuit closed by said obstacle when the latter is moved to danger position, an electric device for holding the circuit closed, a recorder, and a switch for rendering the device inactive and arranged when moved to operate the recorder.

3. An automatic train stop system comprising a track device, a generator, a switch arm arranged to be moved by said device when the latter is moved to active position, a signal circuit arranged to receive current from the generator, a pair of spaced contacts in said circuit and arranged to be bridged upon movement of the arm, and an electric latch for holding the arm in circuit closed position, the circuit of said latch being controlled by said arm.

4. An automatic train stop system comprising a track device, a generator, a switch arm arranged to be moved by said device, when the latter is moved to active position, a signal circuit arranged to receive current from the generator, a pair of spaced contacts in said circuit and arranged to be bridged upon movement of the arm, and an electric latch for holding the arm in circuit closed position, the circuit of said latch being controlled by said arm, and a manually operated switch for breaking the electric latch circuit and thereby release the arm and also to break the signal circuit.

5. An automatic train stop system comprising a track device, a generator, a switch arm arranged to be moved by said device, when the latter is moved to active position, a signal circuit arranged to receive current from the generator, a pair of spaced contacts in said circuit and arranged to be bridged upon movement of the arm, an electric latch for holding the arm in circuit closed position, the circuit of said latch being controlled by said arm, a manually operated switch for breaking the electric latch circuit, and thereby release the arm and also to break the signal circuit, and means rendered active upon closing one of the signal circuits for closing the throttle valve and applying the air brakes of the train.

In testimony whereof we affix our signatures.

ELLIS EDWARD ADAMS.

EDWARD CLAUDIUS BENNETT.
